UNITED STATES PATENT OFFICE.

PAUL HEILMANN-DUCOMMUN AND CHARLES V. STEINLEN, OF MULHOUSE,
ALSACE.

MACHINERY FOR COMBING FIBROUS SUBSTANCES.

SPECIFICATION forming part of Letters Patent No. 224,428, dated February 10, 1880.

Application filed August 10, 1878. Patented in France, November 1, 1877, and in England, November 29, 1877.

To all whom it may concern:

Be it known that we, PAUL HEILMANN DUCOMMUN and CHARLES V. STEINLEN, of Mulhouse, Alsace, engine-manufacturers, have invented certain Improvements in Machinery for Combing Fibrous Substances; and we do hereby declare that the following is a full, clear, and exact description of the same, reference being had to the accompanying drawings, making a part of this specification.

Our invention consists, in part, in a method of cleansing fibrous matter by tearing the web asunder, combing the parted ends, repiecing, drawing, parting, combing again, and repiecing in successive places, as hereinafter described.

Our invention further consists in the combination, with a suitable feed apparatus, of a pair of nippers having a movement of translation adapting them to seize and draw the front end of the web, as hereinafter described, and suitable mechanism for operating the said parts; also, in the combination of two pairs of reciprocating nippers, one moving relatively to the other, and suitable mechanism for operating them; also, in the combination of stationary nippers and one or more reciprocating combs, as hereinafter described, and suitable drawing mechanism, and mechanism for operating the above-named parts; also, in the combination, with the stationary nippers, of combs having vertical and horizontal movements and suitable mechanism for operating them, as hereinafter explained; also, in the combination of reciprocating combs and cleaning-brushes, and mechanism for operating said parts, as hereinafter described; also, in the combination of a pair of jaws, one of them provided with an endless apron to change its face, two pairs of drawing-rollers, and a pair of pressure-rollers, all mounted in a moving frame, with suitable mechanism for moving the same, as hereinafter explained; also, in the combination of the drawing and holding nippers and the combs of successive fineness, adapted to operate in succession in the manner hereinafter explained.

A lap or fleece of fibers is drawn, by means of a pair of nippers having a movement of translation, through an apparatus which par-

allelizes, combs, and partially cleans the filaments, separating from the sheets the filaments held by the traveling nippers and partaking of their movement of translation. These filaments, while still held by the nippers, are subjected to the action of one or two combs or rows of teeth to complete their purification. Where two combs are used they are of successive fineness.

The same comb or segment which has combed the filaments held by the nippers, as before described, also combs the front ends, which protrude from the feed apparatus, a second comb being employed for finishing these front ends. During the whole combing operation the front ends of the filaments and the next succeeding portion are held by the feed apparatus and nippers hereinafter referred to in such manner as to avoid waste by preventing any fibers from being drawn out or collected by the combing action in a tangled mass just in rear of the front ends. The reciprocating nippers, returning to their first position, piece up the web, and the drawing and combing operations are repeated, the combs having in the meantime been cleaned.

The machine consists, among other things, of, first, a feed apparatus which parallelizes and may partially clean the filaments, and also prevents them being drawn out or becoming entangled; second, a stationary pair of nippers; third, one or two combing apparatuses; fourth, an apparatus for cleaning the combs; fifth, a nipper having a movement of translation for drawing out and piecing up the web.

In the accompanying drawings, Figure 1 represents a transverse vertical section of the improved combing-machine. Fig. 1^a is a side elevation of the principal operative parts. Fig. 2 is a detail, and Fig. 3 a front view, of the said machine. Figs. 4, 5, 6, 7, and 8 represent the apparatus for cleaning the combs drawn on a larger scale. Figs. 9, 10, 11, 12, and 13 illustrate, on a larger scale, the action of the combing mechanism proper.

The same letters of reference are used in all these figures to designate the same parts.

The feed apparatus, which parallelizes as well as cleans the fibers, if required, and also

sustains the web under the combing action, so as to prevent the fibers from being drawn out, varies according to the state of the material to be operated on, and may consist either of a plain cylinder or a cylinder clothed with plain or saw-toothed helical blades, against which the web is pressed by a series of fingers or pressers, or a porcupine-cylinder, such as shown in Figs. 1, 9, 10, 11, 12, and 13; or any other suitable arrangement of feed apparatus may be used.

In Figs. 1, 9, 10, 11, 12, and 13, B B' represent the two jaws of the stationary nippers, which are made to press lightly the one against the other while the filaments are drawn from the lap, so as to retain the fibers and prevent them from becoming entangled, after the jaws close together, when the combs operate on the front ends, or that portion of the filaments which is in front of the feed apparatus and the nippers B B'. The latter are actuated by a cam, P, acting on a lever, P'.

The combing apparatus for completing the purification of the filaments is shown in Figs. 1, 9, 10, 11, 12, and 13. C C' are two combs or segments with teeth, which may be of progressive fineness, if desired. Each comb has two movements—viz., an up-and-down movement, or vice versa, and a movement of translation—to which may be added a rocking movement. The first of these movements is given to the lower comb by a lever, D, oscillated on a center at d by the action of a cam, D'. The movement of translation is produced by the lever E being made to oscillate on a center at e by the action of a cam, E', and the rocking or oscillating movement of the comb; but this is not an essential part of the present invention. When such motion is required it is obtained by a toothed segment-lever actuating a pinion fixed on the axis of the comb and operated by a cam.

The up-and-down movement of the upper comb is produced by lever T, oscillated on a center, t, by cam T'. The movement of translation is produced by the lever U, oscillated on a center at e by cam U', and the oscillating movement of the comb, (illustrated at C' in dotted lines in Fig. 4,) when such movement is employed, is produced, as in the other comb, by means of a toothed segment-lever actuating a pinion fixed on the axis of the comb and operated by a cam.

Fig. 6 shows the apparatus for cleaning the combs. V is a brush-cylinder, driven in the direction of the arrow. W is a cylinder covered with plush, leather, india-rubber, or bristles. The covering of plush, leather, or india-rubber (which may either be plain or fluted) may either envelop its whole surface or be placed at intervals apart in the direction of the radii of the cylinder. The cylinder W is journaled in a lever, v, at each end, and turns in the direction of the arrow.

As shown in Fig. 4, the arm v' is made in two parts, which is to allow of adjusting the axes Y and w at varying distances apart, the

two portions of the arm v' being secured together by a screw-bolt and serrated joint. v'' represents the pitch-line of a toothed wheel gearing 70 with another toothed wheel, represented by the pitch-line v'''. Instead of wheel v''' gearing directly with wheel v'', two intermediate gear-wheels may be employed, in order to simplify the machine.

The surface speed of brush V is greater than that of cylinder W, in order that it may collect the waste from the latter.

X is a cam actuating lever X' and connecting-rod X''. G, Fig. 1, is a lever-arm carrying the oscillating nipper, which draws out and pieces up the web, said arm moving on G' as a center. H is a crank, which imparts the oscillating movement to arm G, and consequently to the nipper, by means of levers, connecting-rods, and cranks H' H'' H''' H''', the amplitude of the oscillating movement being determined by the position of pivot I, which is fixed adjustably in a slot in H'', so as to enable the point at which the nipper seizes the filaments 90 to be varied. K' is a cam operating a lever, K, by which the nipper is opened and closed.

To regulate the pressure with which the jaw S closes on the jaw R, said jaw S is pivoted to the lever K and connected to a lever, L, fulcrumed on said lever K, and connected therewith at its free end by a slot, l, and clamp-screw l', a set-screw, l'', being provided to accurately adjust the lever before it is locked by the clamp.

M, Figs. 9, 10, 11, 12, and 13, is a pad of india-rubber, to render the pressure elastic. N is an endless apron, of leather or other material, which is shifted at each stroke of the nipper by a clutch, (separately represented in Fig. 2,) 105 consisting of a ratchet-sleeve, 5, engaging with the shaft 6 of the apron N, and having a rigid arm, 7, which receives a reciprocating movement from the connecting-rod 8, so as to rotate the said apron-shaft 6 intermittently in one 110 direction. This apron may be applied to either the upper or lower jaw, or to both the upper and lower jaws, and serves, together with the rollers, to draw along the web of combed fibers.

O O' O'' O''' are pairs of rollers, which, each 115 time the jaws are opened, draw along the web of combed filaments to a sufficient distance, allowing the tail ends of the fibers to project for piecing up the web. Instead of using rollers, the web may be received between two end- 120 less leather aprons as it leaves the nipper.

In Fig. 1, 1 is a conductor upon which the web travels. 2 is a funnel, and 3 4 are two small drawing-rollers. All these parts are carried upon the arms of the oscillating nipper, and move therewith. Thus the web will be formed into a sliver before it is left unsupported and while partaking in the oscillating motion of the nipper.

b b', Fig. 14, are two bars, which, at the moment the oscillating nipper pieces up the web, sustain in a straight and close condition the front ends of the web in front of the nippers B B'.

The action of the machine is as follows: Referring to Fig. 13, the front ends of the fibers project from the feed apparatus and stationary nippers B B', while the tail ends protrude 5 from the oscillating nippers R S. The latter then move back to the position shown in Fig. 9, to piece up the two ends of the web. They then close and nip the web tightly, while the two jaws of the nippers B B' are pressed 10 lightly together, causing them, in conjunction with the toothed or porcupine cylinder, to support the front ends of the fibers and the portion of the web immediately following, in order to prevent loose fibers and tufts formed 15 during the operation of combing being drawn out. The nippers R S then advance a sufficient distance for comb C to enter the web and continue this movement, thus drawing the filaments held by them through the feed apparatus, which thus parallelizes, 20 cleans, and prepares them for the work of the finisher-comb. At this moment (see Fig. 10) the stationary nippers B B' close tightly and the comb commences to move to comb the front ends of the fibers protruding from the said nippers. 25 Immediately there is room between the comb C and nippers B B' for the comb C' it descends, and both combs C C' continue to move along and comb the front ends of the web. The 30 comb C then descends, (see Fig. 11,) comb C' completes the combing of the front ends, and then rises in order to be cleaned, as herein-after described, and repeat the combing operation. The action of the combs may also be varied by making the upper comb descend first and the lower one then rise behind it. The nippers R S, which then arrive at the end of their course, open, (see Fig. 12,) and the rollers O O' O'' O''' draw the combed web along a certain 40 distance, leaving the tail ends protruding for piecing up, after which the nippers move back to the position shown in Fig. 13, in readiness to repeat the operation.

The porcupine-roller or feed apparatus has 45 a forward movement imparted to feed the material to be combed, and it may also have a slight backward movement, in order to draw back a part of the combed fiber, so that when the nippers R S seize a fresh portion of the 50 fiber (see Fig. 9) they may lay hold of rather less than the entire length of the combed ends, and thus have a portion of the web twice combed. This is of advantage when preparing short fibers. If, however, it is desired to 55 eliminate all fibers under a certain length, the distance between the stationary nippers B B' and oscillating nippers R S may be so regulated that the latter shall seize the filaments at such a distance from the nippers B B', according to the length of the fibers to be eliminated, that all fibers not longer than the 60 distance between B B' and the point at which nippers R S begin to act will be rejected.

It will thus be seen that the machine may be 65 adjusted to comb short fibers, or only those which exceed a certain length.

Fig. 6 shows the method of cleaning the

combs. The comb C' is represented in dotted lines at the moment it is about to comb the front end of the web protruding from the nippers B B', after which the comb rises and occupies the position shown in full lines. At this moment the cylinder W is moved on axis Y of the brush V, and occupies the position seen in Fig. 7. The two cylinders then clean the 75 comb, cylinder W recedes, and comb C' returns to the position for repeating the combing operations.

X, Fig. 1, is a plate of metal turning with the brush W on axis Y of the brush V, in order to avoid the deposit of dust upon the web. 80

In the arrangement shown in Figs. 4 and 5 the cleaning is effected by slightly oscillating the comb, so as to present it to the action of the brush V. Thus, in Fig. 4, the comb has 85 risen from the lower to the higher position, and been oscillated slightly and presented to the brush, this oscillating movement being obtained by two toothed segments gearing with two pinions mounted on the ends of the comb-carrier; but this is not essential to our invention. 90

Fig. 8 shows yet another arrangement, in which the brush-roller W receives motion from a toothed wheel, v'''', on shaft Z, which also 95 drives a gear-wheel, v'', on the shaft of the brush-cylinder V. The connecting-rod z causes the arm z' to oscillate on Z as a center, and thus moves the cylinder W, carried by said arm, toward or away from brush V. 100

The action is as follows: The cylinder W describes an arc of a circle in the direction Z' to allow the comb to pass, and then a similar movement in the opposite direction, Z'', to bring it against the comb and assist in the 105 cleaning operation. This done, it again recedes to allow the comb to return to its former position.

In the several cases mentioned the brush V is mounted in adjustable bearings; so as to 110 admit of regulating its position.

Fig. 3 represents a front view of the improved combing-machine.

It will be seen that the brushes are carried on two intermediate frames, a a, so as to allow room beyond the brush-spindle for the comb-levers to work. 115

Instead of making the web pass over the feed or porcupine cylinder, it may pass beneath, and the center of oscillation of the nippers may 120 be brought nearer the front of the machine. According to this process the filaments are drawn by nippers through an apparatus which parallelizes and also cleans them, if desired, this apparatus consisting either of a cylinder 125 with overlapping pressers, or of other kind, according to the state of entanglement, the degree of impurity, or the nature of the fibers. This preparatory treatment, which parallelizes and prepares the filaments for the finishing-comb, effected, they are drawn while still held by the nippers, and are parted and combed. The combs are then stripped or cleaned, and, 130 lastly, the nippers return with the tail ends of

the filaments for piecing up the web, and re-commence the operation on the front ends of the combed filaments left protruding from the feed apparatus. Throughout the combing operation the front ends of the filaments and the portion of the web next thereto are supported by the feed apparatus and stationary nipper, to prevent any loose fibers being drawn out or collected in tufts near the front ends 10 of the filaments, thus avoiding waste.

The mechanical parts comprising the machine have been described, and special importance is attached to the reciprocating nippers or any equivalent attaining the same result. 15 By "reciprocating nippers" is understood two jaws capable of seizing the filaments close up against the stationary nippers, or, if the jaws of the latter be opened, of seizing the filaments at the surface of the feed or porcupine cylinder. We would remark that only nippers admit of seizing the filaments close enough to the cylinder to draw them between its teeth. Two cylinders, or one cylinder with an endless apron, would bring the tangent 20 points at too great a distance therefrom to allow of this being done with short filaments.

The following is what we claim as new and desire to secure by Letters Patent:

1. The process of cleansing and treating a 30 web of fibrous matter by drawing it asunder, combing the parted ends, repiecing it, drawing, parting, combing, and repiecing in a new place, and so on, in succession.

2. The method of cleaning a web of fibrous 35 matter by repeated parting, combing, and repiecing in successive places, and subsequently subjecting it to pressure to complete the effective joining of the web or sheet.

3. The combination, with a suitable feed apparatus, of the traveling nippers R S and a 40 mechanism for imparting a movement of trans-

lation thereto, substantially as herein described, adapting said nippers to seize and draw the front ends of the filaments, as explained.

4. The combination, in a machine for combing or straightening fibers, of two pairs of reciprocating nippers, one moving relatively to the other, and suitable mechanism for operating them, substantially in the manner described.

5. The combination of the nippers B B', one or more reciprocating combs, C C', suitable drawing mechanism, and mechanism for operating the above-named parts, substantially as 55 and for the purposes set forth.

6. The combination of the nippers B B', combs C C', having vertical and horizontal movements, and suitable mechanism for operating the above-named parts, substantially as 60 and for the purposes set forth.

7. The combination, with the combs C and C', of two cleaning-brushes, one moving around the other, and suitable mechanism for operating them, substantially as shown and described.

8. The combination of the jaws R S, an endless apron, N, on one of the said jaws, the two pairs of drawing-rollers O O' O'' O''', and the pressure-rollers 3 4, all mounted in a movable frame, with suitable mechanism for 70 imparting motion thereto, substantially as and for the purposes set forth.

9. The combination of stretching and holding nippers R S and B B' and combs C C', of successive fineness, adapted to operate in succession, the finer after the coarser, on a thinner portion of the web.

PAUL HEILMANN-DUCOMMUN.
CHARLES VINCENT STEINLEN.
